UNITED STATES PATENT OFFICE.

BENGT A. PETTERSSON, OF LUND, SWEDEN.

FAUCET.

Application filed July 15, 1924. Serial No. 726,146.

To all whom it may concern:

Be it known that I, BENGT A. PETTERSSON, subject of Sweden, residing at Lund, in the county of Malmohus and Kingdom of Sweden, have invented certain new and useful Improvements in Faucets, of which the following is a specification.

My invention relates to improvements in faucets.

- 10 An object of the invention is to provide a faucet having discharge means adapted to be inserted in cans and the like to prevent the formation of foam or scum when being filled with liquid.
- 15 A further object of the invention is to construct the faucet so the discharge means may be removed to a remote position when not in use, at the same time rendering the faucet inoperative.
- 20 Another object of the invention is to provide a device of the above character which is simple and durable in construction, efficient and sanitary in use, and inexpensive to manufacture.
- 25 Other objects and advantages of the invention will be apparent during the course of the following description.

In the accompanying drawings forming a part of this specification and in which like numerals are employed to designate like parts throughout the same,

Figure 1, is a front elevation of a tank with my faucet attached, showing the same in an inoperative position,

35 Figure 2, is a front elevation of a tank showing the faucet in an operative position,

Figure 3, is a longitudinal sectional view of the faucet when open,

Figure 4, is a cross section on line 4—4 of Fig. 3,

Figure 5, is a side elevation of the faucet,

Figure 6, is a top view of the same,

Figure 7, is a longitudinal sectional view of the faucet closed, and,

45 Figure 8, is a cross section on line 8—8 of Fig. 7.

In the drawings, wherein for the purpose of illustration I have shown a preferred embodiment of my invention the letter A designates a supply tank or container for holding liquid, with my improved faucet B attached thereto, for drawing the liquid from the tank. When filling milk cans or similar receptacles C, it is customary to attach a length of hose to the discharge end of the

faucet, to be placed in the can, so the liquid will be discharged near the bottom thereof, and thereby, prevent the formation of foam or scum. In order that the hose may be more conveniently handled and kept in a sanitary condition, the faucet is constructed so the hose may be vertically raised when not in use, so as to be in a remote position from the floor.

Referring more particularly to my invention the numeral 5, denotes the tapered body of the faucet B provided midway its length with a lateral extension 7 having a passage 7' communicating with the longitudinal bore 8 through the body. The extension is 60 provided with a circumferential flange 9 and exterior screw threads 10, through the medium of which the body is connected with an opening in the tank or container A.

65 To control and regulate the flow of liquid through the faucet a valve is provided consisting of a tapered valve sleeve 12 revolvably mounted in the bore 8, having its lower end extended below the edge of the body and exteriorly screw threaded, as at 13, to 70 receive the screw threaded ring 14 which clamps the sleeve in place. The sleeve provides a seat for the rotatable plug 15, equipped at its upper end with an operating handle 16, disposed at right angles thereto. 75 The plug is provided with a longitudinal bore 17, open at its lower end, and openings 18 and 19 through the sides of the plug and sleeve 12, when in registering position with the passage 7', establish communication between the tank and the bore 17 of the plug. The bore 17 at its lower end is provided with a nipple 18 to receive an end of the 80 depending hose or pipe 19 which is seated on the shoulder 20 within the nipple. The 85 plug and sleeve are normally connected together by the pin 21 projecting from the side of the plug near its upper end and seated in the slot 22 in the upper peripheral edge of the sleeve. Thus, it is seen, that 90 rotary movement of the plug, through movement of the handle, is imparted to the sleeve, so the openings may be brought simultaneously into registering position with the passage 7' of the extension. To prevent vertical movement of the plug when the valve 95 is in operative position, the handle is provided with a depending stem 23 disposed in close proximity to the body 5, having 100 oppositely extending arms 24 and 25 at its 105

110 length of hose to the discharge end of the

lower end, the inner arm 24 slidably engaging the underside of the annular flange 26 surrounding the peripheral edge of the body. When the valve is given a half turn, the 5 openings will be in nonregistering position and the arm 24 will be disposed in alignment with the slot 27, through the flange 26 and the plug may then be raised vertically to elevate the discharge pipe to a remote 10 position from the floor. If it is not desired to raise the pipe, the valve may be locked by passing a suitable lock, not shown, through the aperture 28 in the arm 25 and the registering aperture 29 in the lateral extending plate 30, cast integral with the body. 15 Stop lugs 31 are provided on opposite sides of the body to limit the rotary movement of the valve.

In use, it will be readily seen, the turning 20 of the operating handle will rotate the sleeve and plug in unison, to close or open the valve of the faucet. When completely closed the plug may be raised vertically to lift the hose upwardly, while the sleeve remains seated and cuts off the flow of liquid. 25 When open the plug is held seated by the arm which engages the underside of the flange surrounding the upper edge of the body. Thus, a faucet of practical construction 30 is provided, designed so a discharge hose or pipe may be used in filling cans or receptacles from a supply tank, in a highly sanitary and convenient manner.

It is to be understood that the form of 35 my invention herewith shown and described is to be taken as a preferred example of the same, and that certain changes in the shape, size and arrangement of parts may be resorted to without departing from the spirit 40 of the invention or the scope of the subjoined claim.

Having thus described my invention, I claim:

In a faucet, the combination of a tubular body surrounded at its upper end by an 45 annular flange and having a lateral passage communicating with the bore of said body, a valve sleeve rotatably mounted in said body and extending below the lower end thereof, said sleeve having an opening 50 through its side adapted to register with said lateral passage, a nut threaded on the lower end of said sleeve, a plug removably mounted in said sleeve, having a central bore open at its lower end and provided with 55 an opening through its side adapted to register with the opening of said sleeve, means detachably connecting said sleeve and plug together, said plug having its lower end extending below the end of said sleeve and 60 having an internal recess, a flexible discharge pipe detachably fitted in said recess and depending from the plug, a handle formed integral with the upper end of said plug and extending at right angles thereto, 65 a stem formed integral with and depending from said handle adjacent the annular flange of said body, a cross bar formed integral with the lower end of said stem, the inner end of said cross bar engaging the 70 under side of said flange and adapted to register with a slot in said flange when the valve is closed to permit removal of said plug, and a lateral plate extending from said body beneath said slot having an aperture 75 adapted to register with the aperture through the outer end of said cross bar when the valve is closed whereby said valve may be locked in a closed position.

In testimony whereof I affix my signature.

BENGT A. PETTERSSON.
